UNITED STATES PATENT OFFICE

146,993

DESIGN FOR AN AIRPLANE

Luane Eldon Swanson, Cherokee, Iowa

Application September 21, 1945, Serial No. 122,219

Term of patent 3½ years

(Cl. D71—1)

To all whom it may concern:

Be it known that I, Luane Eldon Swanson, a citizen of the United States, residing at Cherokee, in the county of Cherokee and State of Iowa, have invented a new, original, and ornamental Design for an Airplane, of which the following is a specification, reference being had to the accompanying drawings, forming part thereof.

Figure 1 is a top plan view of an airplane, showing my new design.

Figure 2 is a side elevational view.

Figure 3 is a front elevational view.

Figure 4 is a rear elevational view, and

Figure 5 is a bottom plan view thereof.

I claim:

The ornamental design for an airplane, as shown.

LUANE ELDON SWANSON.
